MECHANICAL RAZOR

Rudolf Dreverhoff, Brooklyn, N. Y.

Application October 26, 1933, Serial No. 695,290

4 Claims. (Cl. 30—12)

The present invention relates to improvements in the class of mechanical razors, in which the movement of the cutting blade is longitudinal to the cutting edges and actuated forward by the fingers of the operating hand and backwards by spring power.

The object of the present invention represents a practical and economical mechanical razor, as well as a safety razor, with provisions for a better sliding system, with automatic adjustment of the guide and a provision for protecting the extreme corners of the cutting blade at the cutting side along their movement, for not hurting the skin, and a better arrangement for removing or inserting the cutting blade without having a loose part, and also is provided with a better and simplified spring mechanism for the backwards motion of the blade.

The said provisions are united in a few members arranged in a manner for giving the razor a very narrow flat shape.

The features of my invention will be further disclosed and better explained in the course of the following description, in the appended claims and by the accompanying drawing in which

Fig. 1 is a side elevation of the razor in accordance with the present invention;

Fig. 2 is a section taken on line 2—2 of Fig. 1;

Fig. 3 is the same section on a larger scale;

Fig. 4 is a front elevation with a sketch of a hand for showing how to handle the razor;

Fig. 5 is a side elevation with a cover turned aside to clear the sliding mechanism for removing or inserting the cutting blade or when cleaning the razor.

The razor, which may be made from any suitable metal or material, stamped or molded, comprises a casing 2, a slide 3 carrying a razor blade 5, and sliding together longitudinally to the cutting edges of said blade in a guide formed by casing 2 and a cover 1.

The slide 3 is actuated forward by the fingers of the operating hand and backwards by a flexion spring 4, which is U-shape like set in the casing 2, in the way that the extended ends of spring 4 enter in a cutting out provided in the slide 3 with opening against the ends of said spring 4, whereat the one end of spring 4 serves for pushing back the slide 3, while the other end serves for stopping the motion when slide 3 is in position; so that in the U-shaped spring 4 the back drive and stop are united to simplify this mechanism.

Heretofore is provided a groove at the inside 55 at the cutting out of said slide 3, serving as a

bearing for the driving end of spring 4, and at the same time it is serving as a lock to hinder the slide for falling out or off from its seat, when the cover 1 is turned aside for clearing the sliding mechanism and for removing or inserting the 5 razor blade.

When intended to take a complete cleaning of the sliding mechanism, the slide 3 is also easy to remove or to insert on account of the said cutting out, whereby the engaged ends of the spring 4 are cleared and the slide 3 can be drawn off, without removing the spring 4.

On the slide 3 are provided a number of pins, 10, set in or cast on said slide, for holding the razor blade 5 in position.

Further are provided parallel ribs, 16, longitudinal to and on slide 3, whereon is resting the blade 5, and said blade is held on its seat and guided by opposite ribs, 15 and 12, on the inside of the cover 1, whereat these 20 ribs, 15 and 12, are parallel to the ribs, 16, on the slide 3, but displaced to each other for several reasons, and that is for avoiding clamping the slide 3, for having room for the entering foam of the soap, for diminishing friction and for obtaining a certain elasticity by the blade in producing a bending moment by the distance from rib to rib, and using this elasticity as an automatic adjustment for the guide and the sliding members, when the cover 1 is put or screwed on 30 the casing 2 by a nut 8 on the stud 6.

If, for example, the ribs on slide 3 be placed vis-à-vis to the ribs on the cover 1 and not displaced to them, then would be no elasticity between cover, blade, slide and casing.

Under such conditions, as said example, any variation caused by tightening the cover on its seat would cause squeezing the blade between the ribs, the same would happen when hairs cut off are coming between blade and ribs during the 40 shaving act and the razor would not work.

The cover 1 is arranged to turn aside, swivel like, for opening the razor and for removing or inserting the razor blade or cleaning the sliding mechanism.

Said cover has its seat on adjusting screws 9, which are located on a circle around the stud 7 on casing 2.

The adjusting screws 9 are provided with pivots and said pivots enter into pivot holes provided 50 on the cover 1, to hold said cover in position.

On account of the screws 9 the cover is adjustable for arranging the space for the guide or for the cutting blade, when using different blade thickness.

This would be a second adjustment for the guide, in respect to the automatic adjustment with the aid of the elasticity of the blade.

The cover is opened by slackening the nut 8 on the stud 7, and on said stud 7 is provided a little spring 6 (coiled or any other shape) to lift the cover 1 by disengaging the pivots of the adjusting screws 9 from the pivot holes, so as to be able to turn said cover aside.

10 The cover 1 is shaped outside at the cutting side like a guard (12) along the effective cutting line "Y" for the cutting edges exposed to the skin of the face, and this guard is extended on both sides "X", but drawn forth to cover entirely the corners of the cutting blade along their movement for not coming in contact with the skin.

15 On the cutting side the casing 2 is provided with teeth 11 as guard, which forms with the corresponding guard 12 on the cover 1, the safety 20 razor.

What I claim is:

1. A mechanical razor comprising a casing member and a cover connected thereto by a swivel, both said cover and casing being elongated, one 25 end of each serving as a handle portion and the opposite respective ends being formed to receive a movable blade carriage, said blade carriage having a notch on the rear edge, the upper surface having blade engaging lugs, and a longitudinally 30 extending rib on each side of said lugs, said casing member at its blade carriage receiving end being recessed on its upper surface to accommodate said carriage and a U-shaped spring also received in said recess, one leg of said U being anchored to the casing and the other leg engaging in 35 said notch in said carriage, said cover being grooved on its under face at its carriage receiving end and said grooves forming ribs which are adapted to engage the upper surface of a blade 40 positioned on the carriage, said ribs being parallel to but out of alignment with said ribs on the carriage, said swivel being adapted to be tightened to cause the ribs to engage the blade and cause it to be flexed transversely, the casing having guard 45 teeth at the end adjacent the carriage receiving groove, one end of said blade carriage normally extending beyond one side of said casing and adapted to be engaged by the finger of the user to reciprocate the carriage in one direction, and 50 said spring serving to reciprocate said carriage in the opposite direction.

2. A mechanical razor comprising a casing member and a cover connected thereto by a swivel, both said cover and casing being elongated, one end of each serving as a handle portion and the opposite respective ends being formed to receive a movable blade carriage, said blade carriage having a notch on the rear edge, the upper surface having blade engaging lugs, and a longitudinally 55 extending rib on each side of said lugs, said casing member at its blade carriage receiving end being recessed on its upper surface to accommodate said carriage and a U-shaped spring also received in said recess, one leg of said U being engaged in said notch, the portion of said leg engaging in said notch being held in a little keyway or groove in said notch to bar said carriage for falling off from its seat when the said cover is turned aside, the other leg engaging also in said 60 notch and serving to stop the motion when said blade carriage is in its initial position, said cover being grooved on its under face at its carriage receiving end and said grooves forming ribs which are adapted to engage the upper surface of a blade 65 positioned on the carriage, said ribs being

parallel to but out of alignment with said ribs on the carriage, said swivel being adapted to be tightened to cause the ribs to engage the blade and cause it to be flexed transversely, the casing having guard teeth at the end adjacent the carriage receiving groove, one end of said blade carriage normally extending beyond one side of said casing and adapted to be engaged by the finger of the user to reciprocate the carriage in one direction, and said spring serving to reciprocate said carriage in the opposite direction.

3. A mechanical razor comprising a casing member and a cover connected thereto by a swivel, both said cover and casing being elongated, one end of each serving as a handle portion and the opposite respective ends being formed to receive a movable blade carriage, said blade carriage having a notch on the rear edge, the upper surface having blade engaging lugs, and a longitudinally 10 extending rib on each side of said lugs, said casing member at its blade carriage receiving end being recessed on its upper surface to accommodate said carriage and a U-shaped spring also received in said recess, one leg of said U being engaged in said notch, the portion of said leg engaging in said notch being held in a little keyway or groove in said notch to bar said cover is turned aside, the other leg engaging also in said notch and serving to stop the motion when said blade carriage is in its initial position, said cover being 15 grooved on its under face at its carriage receiving end and said grooves forming ribs which are adapted to engage the upper surface of a blade positioned on the carriage, said ribs being parallel to but out of alignment with said ribs on the carriage, said swivel adapted to be tightened to cause the ribs to engage the blade and cause it to be flexed transversely, the casing having guard teeth at the end adjacent the carriage receiving groove, one end of said blade carriage normally 20 extending beyond one side of said casing and adapted to be engaged by the finger of the user to reciprocate the carriage in one direction, and said spring serving to reciprocate said carriage in the opposite direction, said cover at its blade carriage receiving end on the outside having a guard along the effective line for the cutting edge exposed to the skin, and said guard being extended on both sides but drawn forth to cover entirely the corners of the cutting blade along 25 their movement for not coming in contact with the skin.

4. A mechanical razor comprising a casing member and a cover connected thereto by a swivel, both said cover and casing being elongated, one end of each serving as handle portion and the opposite respective ends being formed to receive a movable blade carriage, said blade carriage having a notch on the rear edge, the upper surface having blade engaging lugs, and a longitudinally 30 extending rib or a number of longitudinally extending ribs on said blade carriage surface, said casing member at its blade carriage receiving end being recessed on its upper surface to accommodate said carriage and a U-shaped 35 spring also received in said recess, one leg of said U being engaged in said notch, and the portion of said leg engaging in said notch being held in a little keyway or groove in said notch to bar said carriage for falling off from its seat when said cover is turned aside, the other leg engaging also in said notch and serves for stopping the motion when said blade carriage is in its initial position, said cover being grooved on its under face at its carriage receiving end and said grooves forming 40

ribs which are adapted to engage the upper surface of a blade positioned on the carriage, said ribs being parallel to but out of alignment with said ribs on the carriage, said swivel being adapted to be tightened to cause the ribs to engage the blade and to cause it to be flexed transversely, the casing having guard teeth at the end adjacent the carriage receiving groove, one end of said blade carriage normally extending beyond one side 10 of said casing and adapted to be engaged by the finger of the user to reciprocate the carriage in one direction, and said spring serving to reciprocate said carriage in the opposite direction, said cover at its carriage receiving end having on the 15 outside a guard along the effective cutting line for the cutting edge exposed to the skin, and said guard being extended on both sides but drawn forth to cover entirely the corners of the cutting

blade along their movement for not coming in contact with the skin, said casing having pivots on its upper surface, said pivots being located on a circle around the swivel center and cast on said casing or provided on adjusting screws set in said casing, said cover having pivot holes positioned opposite said pivots when said cover in position, a little spring being located between said cover and casing around a center stud and serving for lifting said cover and disengaging said pivots from said pivot holes by slackening a nut on said center stud, said nut being adapted to be taken off from said center stud for being able to take the razor to pieces or said nut being adapted to be movably fastened on said casing for forming with 10 the latter one piece. 15
